22, when the latter is in the socket 21, is in electrical communication with the inner portion 23 of the slide and the latter is insulated from the body portion of the slide in any suitable manner, 5 as shown, and the spring contact 20 is carried by this insulated portion of the slide. The circuit is thus closed through the battery contact 14, spring tongues 15 and 20, the conductor strip 23 of the slide to the central contact of the lamp 22 10 and back through the lamp socket 21, body portion of slide 16 to the casing and opposite side of the battery 12. The slot 19 in the casing 10 is proportioned in length to the desired distance through which the slide 16 is adapted to be 15 shifted. The slide 16 when fully retracted withdraws the spring contact 20 from the contact 15 so as to break the circuit. The initial movement of the slide 16 is to close the circuit, as shown in Figure 2 and advance the light source 22 into 20 the focal center of an inner parabolic reflector 24 which has an opening at its center of sufficient diameter to freely receive the lamp 22 therethrough. The reflector 24 is provided with a mat or light diffusing surface and has an annular rim 25 25 of substantially cylindrical form terminating at its outer edge in an outturned flange 26. The rim 25 is adapted to fit snugly through a central opening provided in a screw cap 27 while the flange 26 is adapted to overlap the outer surface 30 of the cap 27 so as to limit the inward movement of the rim or circular band 25 through the cap. The rim 25 and the flange 26 thus determine the position of the inner reflector 24 and the cap 27 35 is so mounted and supported as to hold the reflector 25 in a desired axial position in the flashlight with respect to the primary focal adjustment of the light source 22.

The flashlight is provided with a head 28 of any suitable construction and configuration, and 40 which in the present instance is shown as of hollow shell form. The head 28 is provided with an internal threaded sleeve 29 coaxially disposed in the head and extending from the inner end thereof outwardly or toward the outer end 45 of the head. The cap 27 is threaded into the outer end of the sleeve 29 and may thus be adjusted axially of the flashlight upon the sleeve 29. The inner end of the sleeve 29 is threaded upon the outer end of the flashlight casing 10 50 and may be turned up upon the same to the desired extent for shifting the head axially on the casing and moving the reflector 24, and other parts of the head into the desired adjustment relative to the light source 22.

55 The head 28 also carries an outer and larger reflector 30. The reflector 30 has a highly polished light reflecting surface to provide a large and intense spotlight. The outer edge of the reflector 30 is provided with a rim flange 31 against 60 which may be seated a lens 32 of any suitable construction and which is provided with an outer marginal beveled edge adapted to fit in the central opening in the outer end of the cap 28, as shown in Figures 2 and 3. The cap 28 and other parts of the head and reflector 30 are so proportioned that the lens 32 is clamped in the opening of the head 28 by the reflector 30 when the adjustable cap 27 is advanced outwardly in the head sleeve 29 to bind the rim 25 of the inner reflector against the inner end of the outer reflector 30. The outer reflector 30 has an enlarged central opening which is of less diameter than the internal diameter of the rim 25 of the inner reflector so that the outer edge of the latter may engage and bind against the outer

surface of the reflector 30 near its inner end to hold the reflectors 24 and 30 in coaxial alignment, and also to provide an inwardly extending annular lip 33 which overhangs the surface of the reflector 24 to intercept any rays reflected upon the rim 25 which would strike the surface of the outer reflector 30 when the light source 22 is in its initial position, as shown in Figure 2, or which would be projected from the light source when in its outermost position, as shown in Figure 3, upon the inner reflector 24.

The slide 16 is adapted to be shifted outwardly from the position shown in Figure 2 into the position shown in Figure 3, wherein the light source 22 is at the focal center of the outer reflector 30. At this point, shown at the section line 4-4 of Figure 3, a light source 22 is advanced out of range of the inner reflector 24 so that practically no light rays are projected upon the inner reflector and consequently any rays from the inner reflector cannot affect the spotlight rays which are projected from the outer reflector 30. It will also be noted that when the light source 22 is retracted into the reflector 24, at the focal center thereof, as shown by the line 25 34 in Figure 2, the light rays from the lamp 22 will be diffused and reflected from the mat surface of the inner reflector 24 to provide a mild field of light within the range of lens 32 and, as the light source is out of range of the outer reflector 30, there will be no concentric light rings, or the like, projected upon the diffused light field when the inner reflector is used. Thus the flashlight may be adjusted to provide a light field of moderate intensity but which is uniform 35 throughout and unaffected by any bright polished surface reflections. The lip 33 may of course be proportioned according to the characteristics of the reflector mounting, and relative to the depth of the cylindrical rim 25 so as to 40 obtain the desired results, and substantially completely isolate the reflectors as regards their individual light effects. By this construction the full light intensity value of the light source 22 is obtained for both the diffused light field and 45 the spotlight. The spotlight reflector 30, being the larger reflector, produces a relatively large and intense spotlight which is not materially detracted from by the relatively large central opening through which the diffused light rays from 50 the inner reflector 24 may pass.

Thus, by a flashlight structure of this character the slight axial adjustment of the light source provides a complete and independent diffused light projection for a uniform flood light or a 55 large and intense spotlight without interfering projections from the mat surface reflector. This substantially complete isolation of the reflectors relative to each other has an individual lighting effect as above particularly described and which, 60 while sought after, has not heretofore been accomplished in any composite flashlight structure. The adjustable feature of the flashlight is thus made more positive and certain and the flood and spotlight operations are more individually 65 efficient. While one particular form of slide lamp holder switch mechanism has been described, it is of course understood that this may be varied to suit conditions for use or manufacture. The construction of slide lamp holder and switch 70 herein illustrated and described is disclosed and claimed in the Patent No. 2,125,038 of Emerson H. Tompkins and Irving T. Holihan filed May 11, 1937, Serial No. 142,040.

From the above description it will thus be seen 75

that in the use of the flashlight the slide 16 is normally retracted so as to withdraw the lamp 22 backwardly or inwardly out of the focal range of the inner reflector 24. This position also spaces the spring contacts 15 and 20 so that the light circuit is broken.

When it is desired to use a flashlight the thumbpiece 17 is first advanced into the initial and focal position shown by the line 34 in Figure 2. Here the source of light 22 is at the focal center of the inner reflector 24. As the inner reflector has a mat surface, the light rays are diffused and are projected forwardly through the opening in the center of the outer reflector 30, without striking the same, and are thus projected through the lens 32 to provide an even and modified flood light or light field which is spread over an area sufficient within the range of the flashlight.

20 When a desired object or point of the light field is located, the thumbpiece 17 may then be slid forwardly or outwardly to advance the lamp 22 into the outer focal position, shown on the section line 4-4 of Figure 3. In this position the source of light has been moved entirely out of the inner reflector 24 and is now located at the focal center of the outer reflector 30. The outer reflector 30 has a high polished reflecting surface so that a brilliant spotlight of large field area is projected from the flashlight. The cylindrical rim 25 is substantially covered by the overhanging lip 33 so that the spotlight is not interrupted by any lateral light rays projected from the inner reflector 24.

35 The flashlight may be quickly and easily adjusted into the flood or spotlight positions as the positions are definitely determined by observing the lighting effects during the shifting of the light source from one focal position into the other. 40 Of course the casing and structure may be provided with any suitable means for determining the two focal positions, and also the circuit open position. All of the adjustments are effected from a single thumbpiece by merely sliding the 45 same into different positions, and the simplicity of construction and sturdiness of the flashlight are preserved.

The above description and the accompanying drawings illustrate but one form of the invention, and it is apparent that various modifications might be made within the scope of the invention. One such modification being the reversal in the reflecting surfaces of the reflectors 24 and 30 so that if desired the inner reflector 24 may be provided with the highly polished reflecting surface while the outer larger reflector 30 may have the mat light diffusing surface. This arrangement would not disturb the arrangement between the light source 22 which is adjustable into and out of the focal centers of the reflectors, and wherein the reflectors are shielded against the reflections which otherwise would pass between the reflectors and tend to disrupt or distort the uniform flood light or the spotlight projected from the respective reflectors.

What is claimed is:

1. In a flashlight, a casing having a head thereon, a pair of reflectors mounted coaxially in the head, the inner reflector being small and having a mat light diffusing surface and the outer reflector being larger and having a highly polished light reflecting surface, a light source adjustably mounted in the head for movement along the axis thereof into independent focal adjustments with respect to the inner and outer reflectors, whereby

to obtain a flood light from the inner reflector and a spotlight from the outer reflector, and shielding means disposed between the reflectors to intercept light rays from the light source in either focal position tending to strike the reflector of the opposite focal position.

2. In a flashlight, a casing having a head thereon, inner and outer reflectors mounted coaxially in the head with their focal centers spaced axially apart a substantial distance, one reflector having a mat light diffusing surface and the other reflector having a highly polished light reflecting surfaces, a light source adjustably mounted in the head for movement into independent focal adjustments with respect to the inner and outer reflectors, whereby to obtain either a flood light or a spotlight, said outer reflector having an inner part projecting into the inner reflector a substantial distance to constitute shielding means disposed between the reflectors to intercept light rays from the light source in either focal position tending to strike the reflector of the opposite focal position.

3. In a flashlight, a casing having a head thereon, a pair of independent reflectors coaxially spaced apart within the head, the inner reflector being small and having a mat light diffusing surface and the outer reflector being larger and having a polished light reflecting surface, a slide mounted on the casing and projecting into the head, a source of light mounted on the slide in the head coaxially with the reflectors, and circuit closing means including the slide for energizing the source of light and adapted to break the circuit thereof when the slide is fully retracted, said slide adapted to be advanced outwardly toward said head for first closing the light circuit through the source of illumination and adapted to be advanced consecutively into the focal centers of said reflectors for first projecting a flood light and subsequently projecting a large relatively brilliant spotlight from the flashlight.

4. In a flashlight, independent coaxial spaced apart, large and small reflectors facing in the same direction, the larger reflector having an axial opening of sufficient diameter to admit passage therethrough of light rays reflected from the small reflector, one reflector having a polished light reflecting surface and the other reflector having a mat light diffusing surface, the focal centers of said reflectors being axially spaced apart a substantial distance, a light source coaxial with the reflectors, movable supporting means for the light source to move the same from the focal point of one reflector into the focal point of the other reflector and quickly change the character of the projected light field for adapting the flashlight to the illumination desired, and movable switch means for controlling the illumination of the light source coupled to said supporting means adapted to cause movement of the supporting means with said switch means.

5. In a flashlight, a casing having a head shell, a pair of independent reflectors mounted in the head shell in coaxial alignment, with the outer reflector having an opening at its inner end through which reflected light rays from the inner reflector may pass, the focal centers of said reflectors being axially spaced apart a substantial distance, a light source, a movable support for the light source for moving the same from the focal point of one reflector into the focal point of the other reflector, and switch means movably mounted in said casing for controlling the il-

lumination of said light source and having connection to said support adapted to cause the support to move with said switch means.

6. In a flashlight, a pair of parabolic reflectors axially spaced apart, one reflector being small and the other reflector being large with an opening at its central portion through which projected light rays from the small reflector may pass, the focal centers of said reflectors being axially

spaced apart a substantial distance, a source of light, switch means movably mounted on the flashlight for controlling the illumination of said source of light and means moved by said switch means for relatively moving the source of light and the reflectors to shift the light source from one focal point to the other. 5
